UNITED STATES PATENT OFFICE.

EDWARD B. NIMMO, OF BROOKLYN, NEW YORK, ASSIGNOR, BY MESNE
ASSIGNMENT, TO WALTER WINTHROP, OF SAME PLACE.

STYLOGRAPHIC FOUNTAIN-PEN.

SPECIFICATION forming part of Letters Patent No. 226,924, dated April 27, 1880.

Application filed April 26, 1879.

To all whom it may concern:

Be it known that I, EDWARD B. NIMMO, of Brooklyn, Kings county, New York, have invented certain new and useful Improvements 5 in Stylographic Fountain-Pens, of which the following is a specification.

My invention relates to that class of pens in which the case or handle is hollow to contain a supply of ink, while the writing end terminates in a capillary tube with an internal vibrating needle-tongue or fine stylus.

My invention applies to the writing-point, and it aims to improve and cheapen its construction, so as to render the action of the 15 vibrating point and the flow of the ink more perfect, and also to enable fine or heavy writing to be made without altering the point, as well as to enable the pen to be more readily filled with ink, to which ends the invention 20 embodies a number of novel features, as herein-after fully set forth.

In the annexed drawings, Figure 1 represents my improved pen on an enlarged scale, and shown in a position for filling, the tip or 25 writing end being removed and shown in section. Fig. 2 is an enlarged perspective view of the improved writing-tongue or stylus removed from the tip.

As illustrated, *a* is the case or handle of the 30 pen, the hollow interior of which forms the ink-reservoir. *b* is the vent-cap, and *d* the air-tube, all of which are of substantially the usual construction, except that the air-tube terminates a little beyond the end of the case or handle, 35 and is free of any connection with the vibrating point or stylus, which is usually attached on the end of the air-tube.

k is the removable conical tip, which is provided at the apex with the capillary tube *f*, 40 while the base of the tip screws into the end of the handle, as usual.

A is the fine writing-tongue or stylus, which is inclosed within the tip *k*, works in the bore of the capillary tube, and projects slightly from 45 the end of the tube, being capable, as usual, of vibrating up and down therein under the action of the writing. This writing-tongue, however, is of novel construction, and its arrangement with relation to the parts of the case 50 is also novel.

Heretofore the tongue has been attached to the end of the air-tube and free of connection with the removable tip, so that the tongue and its spring and guides remain on the tube when the tip is removed, and thus more or less obstruct the filling-orifice of the handle. According to my invention, however, the tongue is mounted within and is attached to the removable tip, so that when the tip is removed, the tongue being removed with it, the filling 60 end of the handle is thus left comparatively unobstructed, rendering the insertion of the ink more easy, as will be readily understood from Fig. 1 of the drawings. The upper end of the tongue is fixed, as shown, to a small 65 screw-ring, *B*, which screws into the base of the conical tip, and is provided with a projection, *h*, which forms a handle by which the ring may be screwed in or out, and this construction, as will be observed, also forms at 70 the same time a means of adjusting the projection of the tongue from the end of the capillary tube which is both simple and effective.

Heretofore in pens of this class the tongue has been movable bodily lengthwise, its upper 75 end being attached to an elastic spiral spring, while the tongue itself is inflexible.

Another feature of my invention consists in forming the tongue to be laterally and longitudinally flexible, and thus constitute in itself 80 a spring. Accordingly, as shown in the drawings, the upper end of the tongue *A* is fixed to the ring *B*, while its middle portion is made flat and thin and slightly curved sidewise, so as to be capable of bowing or bending laterally within the hollow of the tip, and thus admit of the necessary elastic vibrations of the tongue up and down in the capillary tube, as will be readily understood. This construction, while being simple, is also more effective, 85 as the lateral thrusts of the tongue on the sides of the capillary tube tend to more effectually prevent the hardening of the ink therein, and thus conduces to a better flow.

A further feature of my improved tongue, 90 as may be observed, consists in its being split lengthwise or formed in two distinct halves, as shown, the upper ends thereof being, of course, fixed together on the ring *B*, while the lower ends thereof, which work in the capillary 100

point, are preferably of half-round section, so as to properly occupy the bore of the point, as will be understood. This feature has the advantage of causing a better flow of the ink and enabling fine or heavy writing to be made. Thus, when the pen is held upright, or nearly so, the writing will be fine; but when the pen is held in an inclined position the divided tongue tends to spread, and thus produces a heavy mark, thereby enabling the writing to be shaded and marks fine or coarse to be made, which has not been heretofore possible with this class of pens.

Although I prefer, as will be understood, to use the screw-ring B for attaching the tongue to the tip k, yet some other means of attachment may be used without departing from the main features of my invention.

The case of the pen is preferably formed, as usual, of hard rubber, while the capillary point, tongue, &c., are, of course, formed of a non-corrosive metal.

I lay no claim, broadly, to a tubular plug or holder carrying the vibrating needle or stylus and fixed to or adjustable in the case of the instrument, or in the lower section or tip thereof; but I limit my claim to the special construction of this feature, as below expressed.

30 What I claim as my invention is—

1. In a stylographic fountain-pen, the combination, with a capillary tubular writing-point, of an internal vibrating tongue, A, fixed at one

end and adapted to bow or bend in the middle, or thereabout, whereby the tongue is rendered laterally and longitudinally flexible, forming in itself a spring, substantially as and for the purpose set forth. 35

2. The combination, with the removable tip k, provided with a capillary tube, and an internal vibrating tongue, of the screw-ring B, forming the means of securing the said tongue in the removable tip and of adjusting its position therein, substantially as herein shown and described. 40

3. In a stylographic fountain-pen, the combination, with a capillary tubular writing-point, of an internal double or split longitudinally-vibrating tongue, A, substantially as herein set forth. 45

4. In a stylographic fountain-pen, the combination, with the removable tip k, provided with the capillary point f, of an internally-vibrating tongue, A, fixed within and to the said tip, and sustained thereby independent 50 of the air-tube or handle of the pen, substantially as and for the purpose herein set forth.

5. The combination, with the tip k and spring-tongue A, of the ring B, for holding the spring-tongue in position, substantially as 55 described.

EDW. B. NIMMO.
